James P. Markham, Webster St.,
Milford, N.H. 03055

Filed Apr. 21, 1969, Ser. No. 16,819

Term of patent 14 years

Int. Cl. D8—03

U.S. Cl. D8—230

FIGURE 1 illustrates a front elevation view of my combined aerial cable support and spacer, or similar article;

FIGURE 2 illustrates a left side elevation view of FIGURE 1;

FIGURE 3 illustrates a right side elevation view of FIGURE 1;

FIGURE 4 illustrates a cross-sectional view taken on line 4—4 of FIGURE 1; and

FIGURE 5 illustrates a cross-sectional view taken on line 5—5 of FIGURE 1.

The reverse side is identical to that shown in FIGURE 1.

The cross-sectional views are illustrated to better define the surface configuration of the herein spacer.

I claim:

The ornamental design for a combined aerial cable support and spacer, or similar article, substantially as shown and described.
